UNITED STATES PATENT OFFICE.

WILLIAM G. HULLHORST, OF TOLEDO, OHIO.

DESIGN FOR A DENTAL CABINET.

No. 38,079.

Specification for Design.

Patented June 12, 1906.

Application filed April 11, 1906. Serial No. 311,197. Term of patent 14 years.

To all whom it may concern:

Be it known that I, WILLIAM G. HULLHORST, a citizen of the United States, residing at Toledo, in the county of Lucas and State of Ohio, have invented a new, original, and ornamental Design for Dental Cabinets, of which the following is a specification, reference being had to the accompanying drawing, forming part hereof.

The figure is a perspective view of the dental cabinet embodying my design.

I claim—

The ornamental design for a dental cabinet, as shown.

WILLIAM G. HULLHORST.
